UNITED STATES PATENT OFFICE.

CARL WEBER, OF CHICAGO, ILLINOIS.

CHIMNEY.

No. 823,197.

Specification of Letters Patent.

Patented June 12, 1906.

Application filed June 22, 1905. Serial No. 236,463.

To all whom it may concern:

Be it known that I, CARL WEBER, a citizen of the United States, residing at Chicago, in the county of Cook and State of Illinois, have invented a new and useful Improvement in Chimneys, of which the following is a specification.

My invention relates to an improvement in the construction of the chimney for which Letters Patent of the United States No. 748,242 were granted to me December 29, 1903.

The more important feature of novelty involved in my patented construction is the circumferential air-space about the base portion of the chimney, this air-space being formed by an outer wall and an inner wall united at the upper end of the air-chamber, the union containing a circumferential series of inclined tubular openings affording communication with the air-space of the interior of the upper single-walled section of the chimney at the base of that section and of the latter with the outer air at openings in the outer wall of the air-space, whereby a circulation of air is established through the chimney. The construction thus outlined, while it has proved itself to be generally desirable, is not suitable for some instances of the use of the chimney, and particularly when products of combustion which pass off through the stack are of a character which tends to render them explosive by feeding them with copious quantities of air, such as would be supplied by free air circulation through the chimney. While this air circulation can be controlled by partially or wholly closing the air-inlet openings in the outer wall, the resultant deprivation of the chimney of the cooling tendency of the air causes the heat in the chimney to exert a degree of differential contraction and expansion of the air-space walls so great as to tend to crack and even destroy the union at their upper ends.

The primary object of my present improvement is to provide a construction of the air-space which shall cause its walls to remain unaffected injuriously under the conditions referred to, and my invention consists in the construction whereby this object is accomplished.

Referring to the accompanying drawings, Figure 1 shows my improved chimney by a view in side elevation. Fig. 2 is a vertical section; Fig. 3, an enlarged, broken, and

partly sectional view, diagrammatic in its nature, of that portion of the chimney contained between the ends of the bracket 3 on Fig. 1; Fig. 4, a section taken at the line 4 on Fig. 1, viewed in the direction of the arrow 60 and enlarged; Fig. 5, a section taken at the line 5 on Fig. 1 viewed in the direction of the arrow and enlarged; Fig. 6, a broken enlarged view showing the base or foundation of the chimney in sectional elevation; and Fig. 7, a diagrammatic plan view of the chimney base or foundation, taken at the line 7 on Fig. 6 and viewed in the direction of the arrow.

To construct the chimney A embodying my improvement, a foundation or base C is laid, composed of intersecting layers of horizontal metal T-beams *a* at intervals embedded in concrete *b* and surmounted by a bed of concrete *c*, with the beams in staggered relation from one layer to another, and metal T-beams *d* to form a circumferential series thereof for the outer wall A' of the lower section of the chimney are embedded in the base C along their lower end portions, which are bent to extend obliquely outward, Figs. 6 and 7, the better to anchor them, and between beams *a* and from the embedded portions of these beams they extend vertically upward, preferably to varying heights. To form the inner wall A² for producing the air-space B, metal T-beams *d'* are embedded at their lower ends in circumferential series in the circumference described by the beams *d* in the concrete of the base C to extend vertically upward, preferably to varying heights.

About each series of beams *d* and *d'* is molded concrete *d²* to a convenient height in each molding operation, and at intervals of, say, about three and one-half feet, more or less, I encircle the outer series of beams *d* with similar beams *d³*, reduced to annular form with the ends of each overlapping, as represented at *x* on Fig. 3. These annular beams are applied successively as the concrete is built up by molding to extend to the different points at which the annular beams are to be placed, so that each in being placed finds bearing on the top of the unfinished portion of the wall below it. As the originally-placed beams *d* and *d'* become nearly thus embedded, another vertical beam is applied to each, preferably in the lap-joint relation represented of beams *d¹²* at *x'* on Fig. 3, and the molding of both walls A' A² proceeds to the desired

- height—say about thirty-seven feet, more or less—from which point the outer beams d employed are bent inwardly to an angle, as shown at v on Fig. 3, to deflect them accordingly and bring the upper ends of the bent sections into coincidence with the planes of the vertical beams d' of the lower double-walled portion of the structure. From this point the outer beams extend vertically upward, as beams d^{12} and have concrete molded about them, as already described, with annular beams d^3 placed at intervals about them and more beams d^{12} added until the upper single-walled portion of the chimney attains the desired height—say to about ninety feet, more or less—with an internal diameter of, say, about four to five feet, more or less. Where the beams d are deflected, as at v , an oblique ledge D is molded.
- 20 The description thus far applies also to the construction set forth in my aforesaid patent. In the inner surface of the outer wall A' , below the plane of the ledge D , is formed an annular offset of rectangular cross-section, affording an expansion-chamber B' of somewhat greater diameter than that of the inner wall A^2 , the upper end of which enters the expansion-chamber to the extent of about one-half the height of the latter, thereby leaving room, both laterally and upwardly, for the expansion of the inner wall, which is thus free from the outer wall and remains unaffected by expansion and contraction of the latter.
- 30 35 An opening g is provided in my present as in my said former construction near the base of the chimney for connecting it with the smoke-flue of a furnace, and below the plane of that opening another opening is formed through which to clean the flue, closed by a door h , and at the base of which is provided stone slab i in the chimney-flue; but openings like the opening e shown in Fig. 6, through which the air-space B communicates with the outer air, should be few in number or very small, if provided at all, though they may be partially or wholly closed under certain conditions of the use of the chimney. However, expansion of the inner wall A^2 in the chamber B' so far reduces the outlet into the single-wall section of the chimney for air circulating through the space B as to reduce to the minimum the danger of explosion, hereinbefore referred to.
- 55 55 What I claim as new, and desire to secure by Letters Patent, is—
1. A smoke-stack, having its lower section composed of an inner and an outer wall, constructed and arranged so as to form a circumferential air-space open to the atmosphere and its upper section composed of a single wall which is a continuation of said outer wall, the latter constructed with a ledge arranged to support laterally the top of said inner wall

in such a manner that said top is free to move 65 relatively to the outer wall.

2. A chimney, of the character described, having its lower section composed of an outer wall and an inner wall free at its upper end from said outer wall and forming with the latter an interposed air-space; an expansion-space, above the top of the inner wall, into which the upper end of said inner wall extends, and the upper chimney-section composed of a single wall joined at its base to the 75 upper end of said outer wall.

3. A chimney of the character described, having its lower section composed of an outer wall and an inner wall free at its upper end from said outer wall and forming with the latter an interposed air-space, and its upper section composed of a single wall, a ledge extending obliquely from the upper end of said outer wall and forming the junction therewith of said upper section, said ledge constructed 85 and arranged to support, peripherally, the top of the inner wall.

4. A chimney of the character described, having its lower section composed of an outer wall and an inner wall free at its upper end 90 from said outer wall and forming with the latter an interposed air-space, an expansion-chamber formed in the inner surface of said outer wall, into which the upper end of said inner walls extends, and the upper chimney-95 section composed of a single wall joined at its base to the upper end of said outer wall.

5. A chimney of the character described, having its lower section composed of an outer wall and an inner wall free at its upper end 100 from said outer wall and forming with the latter an interposed air-space, and its upper section composed of a single wall, a ledge extending obliquely from the upper end of said outer wall and forming the junction therewith of said upper section, and an expansion-chamber formed in the inner surface of said outer wall below the plane of said ledge and into which the upper end of said inner wall 105 extends.

6. A chimney of the character described, having its lower section composed of an outer wall and an inner wall free at its upper end from said outer wall and forming with the latter an interposed air-space and its upper 115 section composed of a single wall, a ledge extending obliquely from the upper end of said outer wall and forming the junction therewith of said upper section, and an annular offset of rectangular cross-section on the inner surface of said outer wall adjacent to said ledge and forming an expansion-chamber 120 into which the upper end of said inner wall extends.

CARL WEBER.
